CLAIM

I claim the ornamental design for a hub with computer ports, as shown and described.

DESCRIPTION

FIG. 1 is front, left elevational view of a hub with computer ports showing our new design;

FIG. 2 is a front elevational view thereof;

FIG. 3 is a rear elevational thereof;

FIG. 4 is a left elevational view thereof;

FIG. 5 is a right elevational view thereof;

FIG. 6 is a top plan view thereof; and,

FIG. 7 is a bottom plan view thereof.

wherein the broken lines shown in the drawings are for illustrative purposes only and form no part of the claimed design.
